UNITED STATES PATENT OFFICE.

ERNEST G. BUTTON AND FRED M. HUNTOON, OF RIVERSIDE, CALIFORNIA.

ORCHARD-HEATER.

1,091,731.

Specification of Letters Patent. Patented Mar. 31, 1914.

Application filed July 28, 1913. Serial No. 781,556.

To all whom it may concern:

Be it known that we, ERNEST G. BUTTON and FRED M. HUNTOON, both citizens of the United States, residing at Riverside, in the county of Riverside and State of California, have invented new and useful Improvements in Orchard-Heaters, of which the following is a specification.

This invention relates to orchard heaters, and the principal object is to provide an orchard heater in which the liquid fuel can be entirely protected from the elements while awaiting the time necessary to operate the same.

15 It is also an object to provide an orchard heater with a truncated pyramidal cover providing an orifice for the insertion of a burner stack and a plurality of openings adjacent thereto for draft purposes.

20 It is also an object to provide the draft opening in the truncated cover with a damper which will absolutely exclude water.

It is a further object to provide an orchard heater with a truncated tubular burner stack provided with diagonally disposed openings therein below its support 25 in the cover, together with a hood for extinguishing the flame therein and covering the stack.

30 In the drawings accompanying this specification and forming therewith the application for Letters Patent: Figure 1 is an elevation of the orchard heater showing the hood broken away, the burner stack in place, and a portion of the receptacle in section. Fig. 2 is a plan view of the same, 35 without the hood. Fig. 3 is a detail sectional view of the damper. Fig. 4 is a plan view thereof, a portion of the damper being 40 broken away.

More specifically in the drawings, 5 designates the receptacle for containing oil, which is preferably of rectangular configuration having tapered sides and formed of 45 an integral folded sheet of metal so there are no seams to leak, the upper edge being turned back or lapped over a wire to form a suitable rim 6. Mounted upon this receptacle is a cover 7 also rectangular in 50 form and pyramidal as to elevation and truncated, the truncation thereon forming a circular opening concentrically arranged to the overlapping edges 8 of the cover, the edges of the central aperture being raised 55 or upturned to a certain extent to provide a watershed 9 and also a finished edge to

receive the bead on the stack 15. On one or more of the pyramidal faces of the metal cover the same is upset slightly and in this domed portion an arcuate slot 10 is struck 30 from a center, which center is provided with a pivot pin 11 on which is mounted the cupped damper 12, the openings 13 in this damper being arranged all to one side of the center and adapted to register with the 35 arcuate slot 10 when the damper is swung to the registering position by means of the handle 14 formed thereon, a number of apertures being preferred so that the amount of air entering each one of the apertures 40 when registered and controlled by the damper may be regulated as desired or required.

The burner stack 15 is of tubular construction and preferably of the slightly 45 conical truncated form shown so that when inserted within the central opening surrounded by the rim 9 the bead 26 formed thereon will rest upon the rim 9 and the stack will be supported, the bead being 50 preferably midway of its top 16 and bottom 17. Around the periphery of the burner and preferably a slight distance above the upper edge of the rim 9 are provided a series of circular openings 10 which are 55 adapted to admit the outside air with its oxygen direct to the interior of the burner. Below the supporting line and intermediate of the lower end 17 other apertures are provided, the first below the support being one 60 or more circular apertures 19 preferably placed above the inclined and elongated slots 20 and 21, two pairs of these slots being shown in the burner and preferably oppositely disposed to one another and inclined 65 in opposite directions, as clearly shown in 70 Figs. 1 and 2.

To provide an extinguisher for the flame 75 a hood 22 is provided having a depending flange which fits loosely over the open top of the burner stack 15 and rests upon the cover adjacent the rim 9. It will thus be seen that when the hood is in place and the damper closed no water can enter the receptacle and cause injury to the contained oil, 80 it being customary to fill the heaters to anticipate the coming of a low temperature, and if rain precedes the latter, and water enters the receptacle the oil must be separated therefrom involving extra expense, 85 or the heater may boil over.

The inclined slots placed close to the bot-

tom of the burner increase the amount of draft automatically as the oil is lowered and becomes "heavier" and do not become clogged, as well as admit the air from the 5 dampers to the burner stack in a whirling or spiral movement and causing a more intimate and efficient mixture of the volatile elements.

What we claim is:

- 10 1. An orchard heater, comprising a receptacle, a truncated cover having a central aperture and adapted to closely fit the upper rim of said receptacle and having draft openings oppositely disposed to each other, draft dampers provided with a plurality of apertures adapted to control and register with said draft apertures in said cover, and a tubular tapered burner stack adapted to engage said central aperture intermediate of 15 the ends of said burner stack and having a plurality of apertures immediately adjacent and above its support on said cover, and circular apertures disposed immediately below its support and a plurality of elongated 20 apertures oppositely inclined on the opposite portions of said burner stack.
- 25 2. An orchard heater, comprising a metal receptacle, a cover therefor provided with domed portions having arcuate slots therein, a damper pivoted on the center from which each said arcuate slot is struck having apertures therein, and means to move said damper to register said apertures with said arcuate slot or close the same against the admission of water.
- 30 3. An orchard heater, comprising a receptacle, a cover therefor provided with domed portions each having an arcuate slot cut in its elevated portion, a rotatable draft damper having openings to one side of a line

intersecting the center, means to pivot said damper at its center at the point from which said arcuate slot is struck, and a handle on said damper to move the same.

4. An orchard heater, comprising a fuel receptacle and a pyramidal cover therefor having a centrally disposed opening therein and a plurality of draft openings, a burner stack mounted in said centrally disposed opening, said burner stack being provided with a plurality of inclined slots below 50 said cover, and pivoted dampers controlling the draft openings in said cover.

5. An orchard heater, comprising a fuel receptacle and a cover therefor, said cover having a centrally disposed opening therein and a plurality of draft openings, and a burner stack mounted in the centrally disposed opening, said burner stack being provided with a plurality of inclined slots below 55 said cover.

6. An orchard heater, comprising a fuel receptacle and a pyramidal cover therefor, said cover having a centrally disposed opening therein and a plurality of draft openings, a tapered burner stack mounted in said centrally disposed opening, said burner stack being provided with a plurality of circular draft openings above the cover, and a plurality of inclined slots below 60 said cover, and pivoted dampers controlling the draft openings in said cover.

In witness that we claim the foregoing we have hereunto subscribed our names this 11th day of July, 1913.

ERNEST G. BUTTON.
FRED M. HUNTOON.
